APPARATUS FOR THE CARBONIZATION OF
COAL, PEAT, WOOD, AND THE LIKE

Charles Burton Winzer, London, England

Application March 10, 1930, Serial No. 434,689,
and in Great Britain March 22, 1929

9 Claims. (Cl. 202—115)

This invention relates to the carbonization of coal, peat, wood and like materials, and has for an object to provide improved apparatus whereby the process of carbonization and the collection of the resulting by-products may be carried out efficiently, rapidly and economically.

According to the invention an apparatus for carrying out such carbonization and collection of by-products comprises essentially a series of 10 stationary containers or retorts for material to be carbonized, a travelling tunnel or enclosure within which said stationary containers or retorts are mounted, and means for maintaining a part, or parts, of said travelling tunnel at a temperature high enough to bring about carbonization 15 of the material in such containers or retorts as are at any time within said part or parts of the tunnel or enclosure.

Preferably, the means for heating that part, or 20 parts, of the tunnel which is, or are, maintained at carbonization temperature, comprise a hollow or double wall at said part, or parts, and means whereby products of gaseous combustion, and/or producer gas, at an appropriate temperature may 25 be circulated through said hollow wall.

If desired, however, one or more furnaces may be mounted for movement with the travelling tunnel at that part, or parts thereof, to be heated.

30 In all cases, the arrangement is such that, owing to the travel or motion of the tunnel, the temperature of each of the containers or retorts is gradually increased and decreased alternately, and means are provided whereby each 35 container or retort may be charged or recharged while at a relatively low temperature.

One or more pipes or ducts communicate with each container for collecting and leading off gaseous by-products which are evolved while its 40 contents are at a relatively high temperature, it being very simple, owing to the fact that the containers or retorts are stationary, to ensure that none of the gaseous by-products are permitted to escape into the tunnel, at any rate, 45 at the heated parts thereof.

Preferably also, each container or retort is provided at its upper part with a door through which it may be charged with material for carbonization and at its lower part with a door through 50 which carbonized material may be discharged therefrom, it being desirable that each container or retort should be provided internally with a number of vertically disposed webs, fins or the like for preventing the formation therein of too solid a carbonized mass which would ren-

der difficult the discharge of the container. Such webs, fins or the like may in some cases serve to stiffen and strengthen the container or retort, but, if desired, they may be mounted for motion within the container or retort so that they may 60 serve to break up the carbonized material, and thus to facilitate the discharge of the latter.

If desired, the containers or retorts may be provided with means whereby carbonized material may be discharged therefrom at their upper 65 ends.

In order that the apparatus may function in a more or less continuous manner, the containers or retorts may be arranged in an endless series, of circular or other formation, the travelling 70 tunnel or enclosure being formed in a like manner. Thus while some of the containers or retorts (say two-thirds) are being heated the remainder (say one-third) thereof may be at a relatively low temperature and be then discharged, and recharged with fresh material. 75

In such a case it is desirable that means, such as transverse sliding doors in the tunnel, should be provided whereby some (say one-third) of the containers or retorts which are not being 80 heated may be isolated from the remainder for discharging and/or recharging. By such means, the ingress of cold air into the heated part of the tunnel or the egress of hot gases therefrom may be prevented during discharging and recharging operations. 85

Apparatus according to one form of the invention is illustrated by the accompanying diagrammatic drawings of which:—

Figure 1 is a part sectional plan view; and 90
Figures 2 and 3 are sectional elevations on the lines 2—2 and 3—3 of Figure 1, respectively.

An annular tunnel or enclosure 11 of inverted U-shaped cross-section is mounted upon wheels such as 12, 12 (Figure 2) which run on rails 13, 95 13, for rotary motion about its own axis over a continuous circular series of containers 14 for material to be carbonized, the tunnel 11 being provided with an internally toothed ring, indicated at 15, with which meshes a pinion (not 100 shown) of gearing 16 through which motion is imparted to the tunnel 11.

The tunnel 11 is provided with an interior wall 17 which is preferably also of inverted U-shaped cross-section (Fig. 2) and which extends for approximately two-thirds of the total length of the tunnel, the space between the inner wall 17 and the tunnel 11 being stopped off at its ends, as indicated by broken lines at 18, 18, Figure 1. A gas pipe 19, connected through branch pipes 20, 110

a common swivel joint 21, and a supply pipe 22 with a source (not shown) is adapted to supply hot gases, such as producer gases, to the upper part of the space between the inner and outer walls 17 and 11 of the tunnel; for which purpose further branch pipes 23 lead off from the pipe 19 at intervals and communicate each with an opening 24 (Fig. 2) in the outer wall of the tunnel 11. From these openings 24 hot gases pass 10 downwardly between the inner and outer walls 17 and 11 to the lower part of the space there-between, where they pass through openings 25 in the inner wall 17 and then upwardly over and around the containers 14 and finally out of the apparatus through a chimney 26 (Fig. 1). Each 15 pipe 23 is provided with a cock 27 for controlling the passage of gases therethrough, and at the delivery side of said cock 27 a further branch pipe 28 is connected therewith. The branch 20 pipes 28 communicate with an air pipe 29 supplied with air by means of further branch pipes 30 connected with a source of supply in the same manner as are the gas branch pipes 20, whilst the flow of air through each branch pipe 28 is 25 controlled by a cock 31. It will thus be observed that the temperature of the double-walled portion of the tunnel 11 and that of those of the containers 14 which at any time are within said portion, may be controlled as desired. If 30 desired, gases other than air may be supplied via the pipe 29 and branch pipes 28. As the hot gases pass first between the inner and outer walls 17 and 11 of the tunnel before entering the interior of the latter, the temperature prevailing in 35 the tunnel 11 may readily be maintained at a constant value. In order to prevent the ingress and egress of gases from the interior of the tunnel 11, it is provided with flanges 32, 32 which extend downwardly therefrom into annular sand 40 baths 33, 33 as shown in Figure 2. Each of the containers 14 extends across an annular well 34, communication between which and the interior of the tunnel 11 between adjacent containers 14 is prevented by cover or seal plates 35 extending 45 over the well 34.

Each of the containers 14 is provided with a top lid 36 for charging and with a bottom lid 36a for discharging. For charging, a hopper 37 (Fig. 3) is mounted upon the single walled portion 50 of the tunnel for delivery of material to be carbonized into a single container 14 at a time through the top of the tunnel 11, a shutter 38 serving to control the delivery of material from the hopper 37, whilst a door 39 is provided in the tunnel 11 to provide access to the containers 14. Preferably, means (not shown) are provided for opening and closing the lid of the container 14 below the hopper 37 without necessitating the 55 opening of the door 39, in order to prevent loss of heat due to the passage of cold air into, and hot gases out of, the tunnel 11.

In order that loss of heat from the interior of the tunnel 11 may be avoided as far as is practicable during the discharge of the containers 14, 60 sliding doors 40, 40 are provided in the single walled part of the tunnel whereby a group of containers 14 may be isolated (see particularly Figure 3 of the drawings.) Any desired means (not shown) may be provided for opening and closing the bottom doors 36a of the containers 14 between the closed doors 40, 40, and the discharge is made into the buckets 41 of a circular endless conveyor disposed in the lower part of the well 34 beneath the series of containers 14. A second 65 bucket conveyor, indicated at 42, is arranged be-

neath the conveyor 41 to receive the contents of the latter and to convey them away from the apparatus.

Each container 14 is formed internally with longitudinal ribs or fins 43 (see Figure 1) to prevent the formation thereon of too solid a carbonized mass, and for strengthening purposes. The containers 14 are connected in groups of three (Fig. 3) by offtake pipes 44, two for each group, for leading off fluid by-products evolved during the carbonization process. These pipes 44 lead to a common pipe 45 encircling the series of containers 14 and from which offtake pipes 46 lead to receivers for the by-products or to distilling apparatus.

In operation, rotary motion in an anti-clockwise direction is imparted periodically to the tunnel 11, the containers being charged and discharged during the periods at which the tunnel 11 is stationary. It will be noted that once the apparatus is in operation there is no need for the temperature of the containers 14 ever to be reduced below a value at which the evolution of gaseous or liquid by-products first takes place. For this reason an apparatus according to the invention may be worked very economically, little or no heat waste occurring.

It is desirable in most cases that the containers or retorts should be formed from cast iron, and as an example of the temperature variation of the containers or retorts as the tunnel is moved thereover, a container or retort may be discharged at a temperature of about 200° C. and then after being recharged, and as a result of the passage of the heated portion of the tunnel thereover, may reach a maximum temperature of about 600° C., a sufficient length of the unheated part of the tunnel passing thereover before the doors 40, 40 reach the container or retorts for the latter to have cooled to a temperature of 200° C. ready for discharge.

It will be noted that the apparatus may readily be arranged for a ground level at the line A—B or at the line X—Y (Figure 2).

It will be observed also that owing particularly to the use of stationary containers or retorts, there is very little risk of contamination of the by-products or of the carbonized material obtained.

What I claim is:—

1. An apparatus for the carbonization of coal and other carboniferous materials and for the collection of the resulting by-products comprising, in combination, an annular enclosure mounted for rotation about a vertical axis; means for rotating said enclosure periodically about said axis; a circular series of stationary vertical retorts within the enclosure; each retort being chargeable at the top and dischargeable at the bottom; means fixed to the rotary enclosure for charging the retorts from outside the enclosure; means for dividing the enclosure into a charging zone, a carbonizing zone and a discharging zone so as to isolate a group of the retorts from the remainder of the retorts for discharging said group of retorts; means for maintaining the carbonizing zone at a carbonizing temperature; and means for conveying away gas from the retorts.

2. Apparatus as claimed in claim 1 wherein the means for dividing the enclosure into charging and discharging zones comprises at least two sliding doors which are movable across the enclosure from the outside to shut off a group of retorts from the remainder.

3. Apparatus as claimed in claim 1 wherein the means for maintaining the temperature comprises a hot gas pipe extending in a circle around the inside wall of the annular enclosure and rotatable therewith, with branch pipes at intervals leading into the enclosure near the top thereof, and branch supply pipes leading to the central axis of the enclosure, a swivel connection at the central axis permitting connection of the rotatable hot gas pipes with a stationary main supply pipe. 80
4. Apparatus as claimed in claim 1 wherein the means for maintaining the temperature further comprises a circular air pipe extending around the inside wall of the annular enclosure and rotatable therewith, with branches leading to the hot gas inlets near the top of the enclosure and branch supply pipes directed towards the central axis of the enclosure, and adapted to be connected with a stationary main air supply pipe. 90
5. Apparatus as claimed in claim 1 wherein the enclosure is double-walled for the greater part of its circumference providing a gas jacket and single-walled for the remainder, the charging and discharging means being arranged for the most part above and below, respectively, the single-walled section. 95
6. Apparatus as claimed in claim 1 wherein the means for conveying away gas from the retorts comprises a circular stationary pipe and offtake pipes connected with said circular pipe and extending upwardly through the enclosure for connection with the individual retorts, other offtake pipes outside the enclosure connected to the circular pipe for conducting gas from the retorts to other apparatus. 100
7. Apparatus as claimed in claim 1 wherein the retorts are arranged in groups of three with two offtake pipes for each group connected by lateral branches with the retorts near the tops thereof. 105
8. Apparatus as claimed in claim 1 wherein the rotatable annular enclosure has an outer and an inner wall each of inverted U-shape in cross-section spaced apart to provide a space for the circulation of hot gases, the arrangement being such that the hot gases may be introduced near the top of the enclosure between the two walls, and flow downwardly to points near the bottom of the enclosure and there pass through the inner wall and around the stationary retorts; a chimney in the top of the enclosure communicating with the space immediately around the retorts. 110
9. Apparatus as claimed in claim 1 wherein the several retorts rest upon and extend across an annular well which is closed by cover plates between the retorts; and the means for conveying away gas from the retorts comprising pipes which extend up through the well into the enclosure. 115
